US0D1082150S

(12) **United States Design Patent** (10) **Patent No.:** **US D1,082,150 S**
(45) **Date of Patent:** **** Jul. 1, 2025**

(54) **BACK SCRATCHER**

(71) Applicant: **Shenzhen Yuecheng Yuezhen Industrial Development Co., Ltd.**
Shenzhen (CN)

(72) Inventor: **Zhanyue Li**, Guangdong (CN)

(**) Term: **15 Years**

(21) Appl. No.: **35/521,569**

(22) Filed: **May 23, 2024**

(80) **Hague Agreement Data**

Int. Filing Date: **May 23, 2024**

Int. Reg. No.: **DM/238084**

Int. Reg. Date: **May 23, 2024**

Int. Reg. Pub. Date: **Jul. 5, 2024**

(30) **Foreign Application Priority Data**
